ABSTRACT OF THE DISCLOSURE

Method of manufacturing a getter vacuum pump to avoid pump wall getter peeling problems by running an initial pumping cycle with the pump wall held above maximum operating temperature of normal cycling while receiving an initial deposit of getter material.

The present invention relates to a method of building getter ion vacuum pumps and more particularly to a method of surface finishing the body of an orbiting electron vacuum pump (hereinafter "orbitron pump").

This application is a continuation-in-part of Ser. No. 702,482 which is a continuation of Ser. No. 483,549.

Orbitron pumps and many other types of getter ion pumps were introduced to the art by R. G. Herb and colleagues at the University of Wisconsin laboratories. These getter ion pumps have the unique advantage that they can pump active and inert gases without the use of hydrocarbon oils, as in diffusion vacuum pumps, and without the use of magnets, as in sputter-ion vacuum pumps. However, a substantial stumbling block to wide commercial use of getter ion pumps is an unfortunate tendency towards short useful life between maintenance cycles.

The relatively short useful life of orbitron pumps stems from the fact that these pumps, like other getter ion pumps, depend upon the evaporation of a getter material and deposition of the material on the pump wall. A film of getter material builds up and then tends to peel from the wall in long strips. In order to analyze this phenomenon, I operated an orbitron pump, then air released it and repeated this procedure several times. Severe peeling occurred. I examined the peeled section under a microscope and found that the getter material (titanium) appeared in distinct striations corresponding to the number of times the pump was cycled. The striations were well bonded to each other, but they had separated from the pump wall indicating poor adhesion between the first layer of titanium and the pump wall (stainless steel).

It is therefore an object of the invention to provide a method of laying down an adherent initial coating of getter material upon the wall of an orbitron pump to condition the wall.

In general, this is accomplished by initially operating the pump itself in a temperature range higher than any operating temperature of the pump. Prolonged operation under this condition builds up a thin coating of getter material over the surface of the pump wall which is adherent to the pump wall and will also be adherent to further layers of getter material which will be deposited in subsequent operating cycles.

For a further description of my invention, reference should be had to the following specification and accompanying drawings wherein:

FIG. 1 is a diagrammatic view of conventional apparatus used in the practice of my invention; and

FIG. 2 is a chart indicating the sequence of steps.

2

Referring to FIG. 1, there is shown a conventional orbitron pump 10. The pump comprises a body 12. Stainless steel piping 14 is soldered to the body for the flow of coolant liquid around the body. Within the pump is a central electrode rod 16 mounted from a flange 20. A power supply (not shown) is connected between the central electrode 16 and pump body 12 so that the central electrode becomes the anode and the body, the cathode of the electrical pump. At least one filament 18 is mounted at the end of the pump from flange 20. The filament 18 is shielded from the anode 16 so that, when the filament is heated, electrons are emitted with sufficient angular momentum to enable them to go into orbit around the central anode. The electrons tend to orbit around the anode until they collide with a gas molecule in the pump or crash into a cylinder 22 of titanium, mounted on anode rod 16.

The positive ions, formed by electron collisions with air molecules, are attracted to the wall 12. The titanium cylinder 22 heats up under the effect of electron bombardment and titanium vapors are emitted from cylinder 22 and condensed on wall 12. The titanium, by physical burial and/or chemical combination, pumps most of the air in the pump.

Bake-out heaters 24 are provided to prepare the pump for each new vacuum pumping cycle. The heaters are in the form of an electric blanket wrapped around the pumps.

In a typical arrangement, the orbitron pump 10 is connected to a vacuum system 26 which may be a bell jar. The vacuum system and orbitron are also connected to a roughing pump 28 and a high vacuum pump 30 through valves 32 and 34, respectively. The pump 28 is typically a cryosorption pump or a rotary mechanical pump with a zeolite inlet trap. The pump 30 may be a diffusion pump, a titanium getter pump, a cryopump, or for purposes of the present invention, another orbitron pump.

The conventional cycling of the orbitron pump, starting from atmospheric pressure is as follows. The vacuum system and orbitron are evacuated through valve 32 by operation of pump 28 until a pressure of about 10^{-3} mm. Hg (torr) is achieved. Then the pump 30 is operated to lower the pressure still further. During operation of the pump 30, the bake-out heaters 24 are run to raise the temperature of walls 12 to about 250–400° C. This bake-out temperature is normally the maximum temperature to which the orbitron is exposed in its various pumping cycles and is hereinafter referred to as the "maximum operating temperature" of the pump. Initially, the bake-out causes the pressure in the orbitron pump to rise as contaminants are driven from the wall of the orbitron at a rate faster than the effective pumping speed of pump 30 (taking into account the conductance of the interconnecting piping thereof). After a short period (1/2 to about 4 hours), the pressure decreases. Then bake-out is terminated. The power is fed to the orbitron and cooling water is admitted to the coils 14 and the orbitron pump is run to lower the pressure therein (and in the system) to blank-off or as low as desired. From time to time, gas may be leaked into the system through a bleed valve (not shown). If the gas is inert, the pump-down can be repeated without the bake-out step. If a full atmosphere of air is admitted to the system, then the bake-out is generally included as part of the next pump-down cycle.

It is the conventional operation described above that produces the problem of titanium peeling at wall 12. I have discovered a method of operating the pump as part of the manufacturing process. Following my process, the pump can go through several normal operating cycles, as described above, and it will be seen that the peeling problem has been substantially eliminated.

My improvement consists of running a special pumping cycle as part of the manufacturing (or reconditioning) process wherein the orbitron pump is actually operated

during a special bake-out. The special bake-out involves heating the orbitron wall to a temperature in excess of the "maximum operating temperature" (e.g. heating to 500° C. as part of the special treatment where the maximum operating temperature is 400° C.).

A preferred embodiment of my improvement manufacturing process is now described. Reference should be made to FIG. 2, which is a chart of the steps of the improved process according to the preferred embodiment. First, the pump body is cleaned by electropolishing technique. The second step is to further clean the body by abrasive blasting. The third step is to remove grit from the wall 12 of the pump body. This can be done, for instance, by washing with alcohol. Then the pump 10 (FIG. 1) is assembled by welding its parts together or brazing with or without vacuum and by capping with the flange 20, using a demountable seal such as a metal gasket. The pump inlet is connected to a vacuum system 26 (which may be no more than a gauge and a bleeder valve) and to the pumps and valves 28-34 as shown in FIG. 1. The pump 28 is then operated (step five) to reduce the pressure in the system to 10^{-3} torr (corresponding to about 10^{-3} torr in the pump 10 itself). Step six comprises operation of the bake-out heaters 24 to heat the wall to 500° C. This heating is continued for at least 3 hours. The pump 30 is operated throughout step six and in most cases, it will be observed that the pressure falls to 10^{-4} torr. If the pressure fails to reach 10^{-4} torr (e.g. because of a low speed pump 30) step six should be continued beyond three hours until 10^{-4} torr or below is attained. During step six, it is advisable to blow air across flange 20 to cool the demountable seal. A small electric fan is sufficient for this purpose. Step seven comprises turning on the orbitron pump 10 and running it at 500° C. This causes a thin initial layer of titanium (a few monolayers) to deposit on the wall. This running of the orbitron pump without the use of coolant also reduces pressure to 10^{-5} torr. Once stable operation of the orbitron is achieved, the pump 30 can be cut off. The orbitron is run hot until it pulls the pressure down to 10^{-5} torr. The reduction of pressure by a full decade in this range indicates that titanium is starting to adhere to the wall 12 of the orbitron. Operation of the orbitron under heat should be continued for 2-3 hours after 10^{-5} torr or better is achieved. Then the bake-out is terminated by cutting off heaters 24 and admitting cooling water to coils 14 very slowly (step eight). Step nine comprises operating the pump until blank-off is achieved. After this, the pump 10 can be turned off and air released and is then ready for normal operating cycles as described earlier.

The net result of my improved manufacturing process is that a very adherent primer coat of titanium is formed on the pump wall 12. Since this coat is formed at temperatures in excess of the maximum operating temperature of the pump, the prime coat will not be caused to strip or peel by any conditions occurring in the normal operating cycle. Cleanliness is essential to the formation of a good primer coat and this is achieved by applying the primer coat at a pressure on the order of 10^{-5} or 10^{-6} torr, a pressure range which is practical for the orbitron to achieve at treatment temperatures on the order of 500° C.

The choice of treatment temperature is preferably at least 100° C. above the maximum operating temperature of the pump. Thus, if it is necessary to bake-out the pump at 350° C. maximum during a normal operating cycle, the treatment temperature used in steps six and seven of my manufacturing process should be at least 450° C. If a step seven at lower temperature is necessary to reach 10^{-5} torr, the step seven should be carried out at no lower than about 375° C.

The pumps 28 and 30 can be combined into a single pump if a molecular pump or cryosorption pump is used. If a mechanical pump 28 or a diffusion pump 30 are used, in-line trapping should be provided to prevent hydro-

carbon vapors from reaching orbitron 10 during the manufacturing process.

The method of the invention has been particularly described in its application to getter ion vacuum pumps of the orbitron type. It should be noted that the method is similarly applicable to other forms of getter ion vacuum pumps and to heated getter source vacuum pumps which operate without any ionization of gasses within the pump, such as the getter pumps which include resistance heated getter cartridge sources.

Since several variations can be made within the scope of my invention, it is intended that the above description and accompanying drawings shall be read as illustrative and not in a limiting sense.

15 What is claimed is:

1. An improved method of manufacturing a getter vacuum pump comprising the steps of cleaning the pump body, assembling the pump and connecting it to outside pumping means, operating said outside pumping means to reduce the pressure within the getter pump to about 10^{-4} torr, heating the getter pump body during the latter portion of the above said pressure reduction at a temperature in excess of the maximum operating temperature of the getter pump body, then operating the getter pump whereby a getter source in the pump is heated to emit getter material therefrom while the pump body is at said elevated temperature to reduce pressure therein whereby an adherent primer coat of getter material is established on the inner wall of the getter vacuum pump body.
- 20 2. The method of claim 1 wherein said elevated temperature is about 500° C.
- 25 3. The method of claim 1 wherein said pump is a getter ion pump.
- 30 4. The method of claim 2 wherein said pump is of the orbitron type.
- 35 5. An improved method of manufacturing or repairing a getter vacuum pump, of the type whose structure and normal operations include means for and the step of heating a getter source in the pump to emit getter material therefrom and condensing it on a wall of the pump, comprising the steps of cleaning said pump wall, assembling the pump and connecting it to an outside pumping means, operating said outside pumping means pump wall at about 500° C. during the latter portion of said pressure reduction step, said vacuum level being selected to be at a pressure no higher than about 10^{-4} torr and being achieved after an initial pressure rise due to commencement of said pump wall heating step and then heating said getter source to emit getter material therefrom to further reduce pressure in the pump while continuing said heating of the pump wall whereby an adherent primer coat of getter material is established on said wall.
- 40 6. An improved method of manufacturing or repairing a getter vacuum pump, of the type whose structure and normal operation includes means for and the step of heating a getter source in the pump to emit getter material therefrom and condensing it on a wall of the pump and also includes means for and the step of bake-out of the pump wall from time to time comprising the steps of
- 45 7. The method of claim 6 wherein said elevated temperature is at least 100° C. higher than bake-out tempera-
- 50 8. The method of claim 6 wherein said elevated temperature is about 500° C.
- 55 9. The method of claim 6 wherein said elevated temperature is about 500° C.
- 60 10. The method of claim 6 wherein said elevated temperature is about 500° C.
- 65 11. The method of claim 6 wherein said elevated temperature is about 500° C.
- 70 12. The method of claim 6 wherein said elevated temperature is about 500° C.
- 75 13. The method of claim 6 wherein said elevated temperature is about 500° C.

8. The method of claim 6 wherein said elevated wall temperature is about 500° C.

9. The method of any of claims 1-3 wherein said further reduction of pressure by operating the pump is at least a decade (power of ten of mm. Hg pressure drop).
